(57) CLAIM

The ornamental design for an alphabetical mount for a holiday ornamental display, as shown and described.

DESCRIPTION

FIG. 1 is a front perspective view of an alphabetical mount for a holiday ornamental display, showing our new design.

FIG. 2 is a back perspective view thereof; and,

FIG. 3 is a right side view, the left side view being a mirror image thereof.

The bottom is flat and unornamented.

The portions of the mount shown in broken lines form no part of the claimed design.
